2,052,500

PEN

Ralph A. Swartwelder, Masontown, Pa.

Application October 23, 1935, Serial No. 46,387

2 Claims. (Cl. 120—42)

The invention relates to a pen and more especially to a fountain pen.

The primary object of the invention is the provision of a pen of this character, wherein the barrel thereof has therein a plurality of chambers or compartments for holding ink and the supply thereof to the pen point is controlled through releasable valves, these being manually actuated so that the ink in the respective chambers or compartments can flow therefrom, the valves being prevented from sticking as the same are operated one upon the other and in this manner the valve of the pen can carry ink of different colors for use in writing.

Another object of the invention is the provision of a pen of this character, wherein plungers are movably fitted within the barrel thereof and such plungers control the valves for regulating the feed of ink from the series of chambers or compartments as provided therein, the pen being readily cleaned to assure perfect writing when the same is in use.

A further object of the invention is the provision of a pen of this character, which is simple in construction, thoroughly reliable and efficient in operation, convenient for use, particularly in the carrying of different colors of ink, strong, durable, and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claims hereunto appended.

In the accompanying drawing:

Figure 1 is a vertical longitudinal sectional view through a pen constructed in accordance with the invention.

Figure 2 is a sectional view on the line 2—2 of Figure 1 looking in the direction of the arrows.

Figure 3 is a fragmentary vertical longitudinal sectional view through one of the chambers or compartments.

Figure 4 is a similar view through another of said chambers or compartments.

Figure 5 is an end view of the feeder.

Similar reference characters indicate corresponding parts throughout the several views in the drawing.

Referring to the drawing in detail, the pen comprises a barrel 10 of tubular or cylindrical form and having an outwardly tapered reduced end 11 in which is fitted the feeder 12 and pen

point 13, respectively. This feeder 12 has passages 14 for the delivery of ink therethrough onto the pen point 13.

The passages 14 in the feeder 12 lead from a series of cells 15 for ink, there being three in number in this instance, and these are housed longitudinally within the barrel 10 and at their filling ends are closed by a removable cap 16 threaded onto the barrel at the open end 17 opposite the end 11. The cap 16 has fitted therein a felt pad 18 to prevent leakage of ink from the open end 17 of said barrel. These cells 15 in the compartments or chambers 19 provided therein will hold and carry ink, one chamber or compartment 19 being for one color ink, another for another color ink, etc.

Operating within each compartment or chamber 19 is a tubular plunger or piston 20 carrying at its inner end a spring seated spherical or ball valve 21, the latter being supported in a cage 22 while each compartment or chamber 19 is closed at its inner end by a spring seated flap valve 23, it having a tripper 24 which is acted upon by the plunger or piston 20 for the automatic opening of the said flap valve 23 and the ball or spherical valve 21 on engagement of said plunger or piston with said tripper 24 so that ink can flow freely from the chamber or compartment 19 to the pen point 13.

Each plunger or piston 20 carries a pivotally mounted trigger 25 which swings inwardly and outwardly through a clearance 26 provided in the barrel 10 and the cell 15. The trigger 25 is readily accessible through the clearance 26 so that the same can be pulled outwardly from the position shown in Figure 3 of the drawing to the position shown in Figure 4 of the drawing and in this position it can be manually manipulated to move the plunger or piston 20 in a direction to operate the tripper 24 for the simultaneous opening of the valves 21 and 23 to permit the flow of ink to the pen point. The plungers or pistons 20 are selectively operable and manually controlled as indicated.

The ink can not flow from the cells 15 within the barrel 10 until a selected plunger or piston 20 has been actuated for the opening of the valves which control the flow of ink to the pen point.

Each clearance 26 is preferably of substantially keyhole shaped formation so that the trigger 25 accessible therethrough can be readily engaged for the manual operation of the plunger or piston 20 carrying such trigger.

Normally the plungers or pistons 20 are re-

moved from the trippers 24 so that the valves 21 and 23 will be closed under the action of the springs associated therewith for maintaining such valves in closed position.

5 What is claimed is:

1. A pen of the character described comprising a barrel having a capped end and a reduced opposite end, a feeder fitting the reduced end, a pen point carried in the reduced end, a plurality of ink cells fitting said barrel and having valves controlling communication thereof with the feeder, tubular plungers working within the cells and having valves and means for moving the plungers to operate the valves in the cells 10 and also simultaneously operate the valves carried 15 thereby.

2. A pen of the character described comprising a barrel having a capped end and a reduced opposite end, a feeder fitting the reduced end, a pen point carried in the reduced end, a plurality of ink cells fitting said barrel and having valves controlling communication thereof with the feeder, tubular plungers working within the cells and having valves, means for moving the plungers to operate the valves in the cells and also simultaneously operate the valves carried 10 thereby and triggers carried by said plungers and accessible exteriorly of the barrel for accommodating said plungers. 5
